UNITED STATES PATENT OFFICE.

ALMA VOGT, OF ST. LOUIS, MISSOURI.

TOY.

1,417,958.

Specification of Letters Patent. Patented May 30, 1922.

Application filed September 30, 1919. Serial No. 327,462.

To all whom it may concern:

Be it known that I, ALMA VOGT, a citizen of the United States, residing at the city of St. Louis and State of Missouri, have 5 invented a new and useful Toy, of which the following is a specification.

This invention relates to improvements in toys and consists in the novel construction hereinafter disclosed.

10 An object of the invention is to provide a toy comprising a body portion which may be made to represent a doll or other object having means for supporting the body on the fingers of the operator, whereby the 15 toy may be manipulated to represent an animate object.

With the foregoing object, as well as additional features in view, I have designed the construction hereinafter described, reference being made to the accompanying drawing, in which—

Fig. 1 is a front elevation.

Fig. 2 is a side elevation, and

Fig. 3 is a fragmentary rear elevation.

25 The body portion 1 may be made of any suitable material, such, for instance, as cast celluloid, and may take any preferred configuration and design. The body is preferably made hollow. In the back wall of 30 the body, near the lower extremity, is a pair of spaced holes 2, and in the bottom of the body are a pair of spaced holes 3, positioned with respect to the body at a point near the upper part of the legs.

35 The first two fingers of the operator may be inserted through the holes 2, the fingers bending at the second joint, and extending downwardly through the holes 3, so that when viewed from the front, the portion of 40 the fingers extending below the body will simulate the legs of the doll or other objects. The first joints of the fingers represent the knee portion of the doll. Separate elements 4 representing the feet, 45 and having openings 5 for the insertion of

the ends of the fingers, are provided to complete the simulation of the extremity of the legs and are arranged to be slipped over and held by the ends of the fingers.

As the body is supported entirely by the 50 two fingers of the operator, the fingers may be manipulated to simulate the legs of the object and the body portion may be moved so that a complete representation of natural movement of legs and the body may be carried out.

By the manipulation of the device, a simulation of dancing or walking or other activities may be represented by the device

I am aware that the device need not be 60 confined to a representation of a human being, but may be made, by slight changes, to represent animals or other animate objects.

What I claim and desire to secure by Letters Patent is:

1. A toy of the character described, comprising a hollow body having two spaced finger holes through the back wall thereof and two spaced finger holes through the bottom wall thereof for receiving the 70 fingers of the operator, all of said holes being separated by integral portions of the wall of the hollow body, said portions of the wall of the hollow body holding the fingers of the operator spaced and constituting 75 bearings against which the fingers of the operator press when manipulating the toy.

2. A toy of the character described, comprising a hollow body having an opening 80 through the back wall thereof, and two spaced finger holes through the bottom wall thereof for receiving the fingers of the operator, said finger holes being separated by an integral portion of the wall of the 85 hollow body and constituting bearings against which the fingers of the operator press when manipulating the toy.

ALMA VOGT.
